UNITED STATES PATENT OFFICE.

HENRY PHILIP HAMBURG, OF MORRIS PARK, LONG ISLAND, NEW YORK,
ASSIGNOR TO CUSHMAN & DENISON MANUFACTURING COMPANY, OF
NEW YORK, N. Y., A CORPORATION OF NEW YORK.

HAND NUMBERING-MACHINE.

No. 857,934.

Specification of Letters Patent.

Patented June 25, 1907.

Application filed October 10, 1906. Serial No. 338,236.

To all whom it may concern:

Be it known that I, HENRY PHILIP HAMBURG, a citizen of the United States of America, residing at Morris Park, Long Island, county of Queens, State of New York, have invented certain Improvements in Hand Numbering-Machines, of which the following is a specification.

This invention relates to a specific means 10 of controlling the operation so that the machine can be set to repeat, duplicate, or number consecutively.

In the accompanying drawing: Figure 1 is a front elevation: Fig. 2, a detail side elevation of the lower part of the sliding frame carrying the numbering wheels, showing one 15 adjustment of the pawls; and Figs. 3 and 4 are transverse sections on the same line showing two other adjustments.

20 *a* is the swinging pawl carrying frame whose side arms *a'* rock upon the shaft *b* of the numbering wheels *x*. This shaft is shown in section, Fig. 2. Its ends run in vertical 25 guide grooves in side plates *c* of the frame.

Links *d* applied to the pawl frame are pivoted at their upper ends to the inner faces of these side plates. The pawl plate *e* is hinged upon a rod *f* carried by the pawl frame and is normally urged toward the wheels by the 30 usual spring *g*.

In Fig. 2, the longest or units wheel pawl of the gang of pawls is marked *h* and is also indicated by the dotted lines *h* in Figs. 3 and 4. Other pawls are, successively, of shorter 35 length as is well understood. On the end of the pawl plate opposite that carrying the units wheel pawl *h*, is a projection *i* extending parallel with the axis of the pawl plate. On the rod *f* upon which the pawl plate is swung

40 is fitted to turn and slide a segmental plate *j* having therein, adjacent its peripheral portion, three apertures marked 1, 2, 3, properly spaced. A coiled spring *k* applied around the rod *b* urges the plate toward or against the 45 end of the pawl plate. By moving the segmental plate *j* outwardly against the tension of its spring, it may be swung upon the rod *f* so that the projection *i* may be entered into either of the apertures 1, 2, 3, thereby deter-

mining the adjustment for repeating, duplicating or numbering consecutively. When, as in Fig. 2, the projection *i* is in aperture 1, the plate *j* is held away from the peripherally recessed controlling wheels *m*, and the pawl plate carrying the gang of feed pawls is free 50 to move to effect uniform operation of the wheels for consecutive numbering. When the projection is in aperture 2, engagement of the segmental plate in the bottom of the recesses in the wheel *m* results in duplication 55 of successive numbers. When the projection is in aperture 3, the pawls are at all times held out of engagement with their corresponding wheel ratchet and, the wheels not being operated, the same number may be repeated indefinitely.

Various devices for controlling the pawl plate to control the gang of pawls with reference to the ratchets of the numbering wheels have been devised but, so far as I know, the 70 specific construction illustrated and described is new.

I claim as my invention:

1. A hand numbering machine comprising the combination of the rotatable numbering wheels, a swinging pawl frame carrying a projecting rod co-incident with its axis, a pawl carrying plate pivotally connected to the swinging frame, a laterally sliding plate mounted on said projecting rod, a spring acting normally to press the laterally sliding plate laterally toward the pawl carrying plate, means whereby the sliding plate and pawl carrying plate may be interlocked at different points and a recessed controlling wheel co-operating with the sliding plate in the different positions to which the latter may be adjusted, substantially as set forth.

2. A hand numbering machine comprising the combination of a swinging pawl frame carrying a rod parallel with the axis of the frame, a pawl carrying plate swinging upon said rod, a spring normally urging the pawl plate toward the numbering wheels, a segmental plate mounted to turn and slide upon 95 said rod at one side of the pawl plate and having three spaced apertures therein adapted to engage a projection on the end of the

pawl plate, a spring normally urging the segmental plate against the end of the pawl plate and a peripherally recessed controlling wheel with which the segmental plate co-
5 operates, whereby adjustment may be made for repeating, duplicating, or consecutive numbering.

In testimony whereof, I have hereunto subscribed my name.

HENRY PHILIP HAMBURG.
